GEORGE W. BLAIR, OF MISHAWAKA, INDIANA, ASSIGNOR TO MISHAWAKA RUBBER
AND WOOLEN MANUFACTURING COMPANY, OF MISHAWAKA, INDIANA, A CORPORA-
TION OF INDIANA

FASTENING DEVICE

Application filed November 27, 1925. Serial No. 71,523.

My invention relates to fastening devices of the type wherein series of fastener elements, on the edges of the parts which are to be joined together, are interlocked and released by movement of a cam member or slider therealong, and has reference more particularly to a fastening device wherein the elements on one of the parts are in the form of loops which may be coils of a spring and the elements on the other part are formed with offset ends which are arranged to engage within the corresponding loops of the fastening elements on the other part, it being understood that the term loop is used herein 15 in its broader sense to include any element which is approximately or substantially loop-like in form.

In fastening devices wherein loop shaped elements are employed, as for example coils 20 of a spring, it is necessary for the opposed series of fastener elements to positively interlock with the loops or coils of the spring. I have accomplished this purpose in the present construction by providing fastener 25 elements which fit between the successive loops or coils and have offset ends which internally engage the loops or coils and turn therein and the space between the outer extremities of the adjoining elements is restricted sufficiently to retain the loop elements or coils between the adjoining elements 30 and prevent withdrawal thereof except through the operation of the slider or cam member.

The principal objects of my invention are, to provide an improved fastener element for use in connection with loop shaped elements or coils of a spiral spring; to insure a positive interlocking of said elements with the 40 loops or coils; to properly guide the loops or coils between the adjoining elements of the other series; to insure flexibility; and in general to provide an improved fastening device comprising loop shaped elements or coils of a spring, and which is simple in construction, 45 strong and durable and serves to effectively connect the parts which are to be joined together.

On the drawings,

Fig. 1 is a perspective view of an overshoe 50

illustrating the application of my fastener;

Fig. 2, an enlarged detail view of a portion of the fastening device and operating member or slider, the latter being partly broken away to disclose the manner in which the elements interlock and release; 55

Fig. 3, a sectional view on line 3—3 of Fig. 2;

Fig. 4, a perspective view of one of the fastener elements which interlocks with the 60 coils of the spring; and

Fig. 5, a plan view of a type of separate element which may be used in place of the coils of the spring.

Referring to the drawings, in which I have, 65 for the purpose of illustration, shown my invention as applied to an overshoe, although it is to be understood that it may be used in connection with other articles or in any place where an automatic fastener is desired, the reference numeral 1 indicates an overshoe as a whole which is divided down the front to provide separable side portions 2 and 3 which have the series of fastener elements 4 and 5 respectively on the forward edges thereof, and these elements are adapted to be interlocked and released by movement of a cam member or slider 6 therealong. 70

The elements 5 are illustrated herein as 75 the coils of a spiral spring but they may be separate elements in the form of loops which are mounted in any convenient manner on the edge of the side portion 3 of the overshoe or other part which is to be connected by means of the fastening device. 80

The elements 4 are in the form of elongated flat members which are of a thickness to fit, without cramping or binding, between the adjoining coils 5 and are mounted on the part 2 so that they are maintained in 90 spaced relation, the distance between the elements 4 being sufficient to permit a coil 5 to likewise engage between adjoining elements 4 without cramping or binding. In the present case the elements 4 are provided adjacent 95 their rear ends with an elongated opening 7 and a slit 8, forming jaws 9—9 which may be clamped upon the enlarged or beaded edge 10 of the part 2 for mounting these elements. It is to be understood, however, that the man- 100

ner of mounting the elements 4 and 5 does not form a part of my present invention and these elements may be otherwise mounted if desired.

- 5 The elements 4 are alike and each is formed at the outer end, with an offset or lug 11 on the underside which extends forwardly and forms the extreme end of the element and said lug is preferably somewhat semi-circular in form as shown in Figs. 3 and 4 so as to have an arcuate rear face 12 rising somewhat abruptly from the side of the element 4 and corresponding somewhat to the curvature of and forming a rearwardly facing 10 arcuate shoulder which engages the inner surface of the loop or coil 5 with which it interlocks, said loop or coil 5 constituting a pair of spaced side portions with a cross portion at the front to confine the lug 11 therein.
- 15 20 The offset end of the member 4 is rounded or inclined at the opposite side from the offset 11, as indicated at 13 and terminates in a rounded edge 14 so that the latter readily engages between adjoining coils or loops 5 and the incline 13 serves to guide the loop in between the adjoining elements 4. At 25 each side the member 4 is rounded or cut away at the edge as indicated at 15 adjacent the point where the coil 5 engages therewith so as to permit a rolling action of the element 4 against the coil and thereby facilitate lateral flexing of the fastener device without binding or cramping.

- 30 The outer end of the member 4 may be 35 conveniently formed by a stamping or punching operation which shifts the portion 11 of the element sidewise and forms the offset, and at the same time produces a somewhat corresponding recess 16 at the opposite side.
- 40 45 This recess, being arcuate or semicircular in form, leaves the lateral edges as indicated at 13 which serve to center the loop 5 as it rides thereover and to guide said loop up into place behind the offset 11 of the next adjoining element 4.

- 50 It will be noted by referring to Fig. 2 that the offset 14 extends downwardly quite close to the upper extremity of the inclined portion 13 of the next element so that the space 55 between the elements 4 is substantially restricted at the outer end with the result that when the coil or loop 5 is engaged between adjoining elements 4 and the latter adjusted to the normal position, the restricted space 60 between the ends of the elements 4 is insufficient to permit disengagement of the loop and the fastening device is thus effectively held against accidental release and the parts cannot be disconnected except by the operation 65 of the operating member or slider 6.

- 70 The slider 6 is of substantially the usual form comprising inner and outer plates 17 and 18 respectively with an interposed wedge shaped spreader 18 and inturned portions 75 85 90 95 100 105 110 - for guiding the outer portion of a loop of the other series of elements to a position behind the rear face of the offset of the adjoining member.
5. In a fastening device of the class described, the combination of opposed series of fastener elements and a slider operable therealong for interlocking and releasing same, said elements of one series comprising successive loops and said elements of the other series comprising substantially flat plates which fit between the adjoining loop elements and terminate in offsets with rearwardly facing arcuate shoulders which engage with the inner faces of the outer portions of the corresponding loops of the other series of elements.
10. In a fastening device of the class described, the combination of opposed series of fastener elements and a slider operable therealong for interlocking and releasing same, the elements of one series comprising members each of which has a pair of laterally spaced side portions and a cross portion at the front, and the elements of the other series each comprising a substantially flat plate adapted to fit between said cross portions of adjoining elements of the other series and said plates having offset ends extending between the said laterally spaced portions of the other series of elements and engaging behind the said cross portions of the latter elements.
15. In a fastening device of the class described, the combination of a coiled spring having the successive coils spaced apart, a series of fastener elements and a slider operable along the coiled spring and series of fastener elements for interlocking and releasing the fastener elements and the coils of the spring, said fastener elements being formed at the outer ends with offset portions forming arcuate rearwardly facing shoulders for engaging the inner faces of the outer portions of the corresponding coils of the spring and said elements having inclined guides at the outer ends for guiding the coils of the spiral spring behind the shoulders of the adjoining elements.
20. In a fastening device of the class described, the combination of a series of wire loops consisting of convolutions of a spring, a series of spaced elements, and a slider operable along the series of loops and spaced elements for interlocking and releasing same, said elements being formed with corresponding inclined guides at the ends for guiding the loops in between the elements and each element having an offset portion at the side opposite the inclined guide of the adjoining element and restricting the space between the outer ends of the adjoining elements so as to lock the loop therebetween.
25. In a fastening device of the class described, the combination of a series of wire loops consisting of convolutions of a spring, a series of spaced elements, and a slider operable along the series of loops and spaced elements for interlocking and releasing same, said elements having corresponding substantially inclined faces at their outer ends for guiding the outer portions of the loops between the elements and having corresponding off-set portions at the outer ends adapted to enter within the corresponding loops close to the inner extremity of the inclined face of the next adjoining element so as to restrict said space at the outer end and thereby lock the loop between the elements.
30. In a fastening device of the class described, the combination of opposed series of fastener elements and a slider operable therealong for interlocking and releasing same, one of said series of elements comprising spaced loop members and the elements of the other series comprising elongated flat members, each of which latter has a substantially semi-circular offset portion at the outer edge fitting within a loop member of the other series of elements.
35. In a fastening device of the class described, the combination of opposed series of fastener elements and a slider operable therealong for interlocking and releasing same, the elements of one series comprising members each of which has a pair of laterally spaced side portions and a cross portion at the front, and the elements of the other series each comprising a substantially flat plate adapted to fit between said cross portions of adjoining elements of the other series and said plates having offset ends extending between the said laterally spaced portions of the other series of elements and engaging behind the said cross portions of the latter elements.
40. In a fastening device of the class described, the combination of opposed series of fastener elements and a slider operable therealong for interlocking and releasing same, one of said series of elements comprising a plurality of plates and the other series of elements comprising a plurality of loops adapted to receive the plates therebetween, said plates being notched at their edges to afford clearance for lateral portions of the loops engaged therewith for permitting lateral bending of the interlocked elements and interlocking means on the plates for engagement with the loops.
45. In a fastening device of the class described, the combination of opposed series of fastener elements and a slider operable therealong for interlocking and releasing same, the elements of one series comprising spaced loop members and the elements of the other series comprising elongated flat members, each of which latter has a substantially semi-circular offset portion at the outer edge fitting within a loop member of the other series of elements.
50. In a fastening device of the class described, the combination of opposed series of fastener elements and a slider operable therealong for interlocking and releasing same, the elements of one series comprising members each of which has a pair of laterally spaced side portions and a cross portion at the front, and the elements of the other series each comprising a substantially flat plate adapted to fit between said cross portions of adjoining elements of the other series and said plates having offset ends extending between the said laterally spaced portions of the other series of elements and engaging behind the said cross portions of the latter elements.
55. In a fastening device of the class described, the combination of opposed series of fastener elements and a slider operable therealong for interlocking and releasing same, the elements of one series comprising spaced loop members and the elements of the other series comprising elongated flat members, each of which latter has a substantially semi-circular offset portion at the outer edge fitting within a loop member of the other series of elements.
60. In a fastening device of the class described, the combination of opposed series of fastener elements and a slider operable therealong for interlocking and releasing same, the elements of one series comprising members each of which has a pair of laterally spaced side portions and a cross portion at the front, and the elements of the other series each comprising a substantially flat plate adapted to fit between said cross portions of adjoining elements of the other series and said plates having offset ends extending between the said laterally spaced portions of the other series of elements and engaging behind the said cross portions of the latter elements.
65. In a fastening device of the class described, the combination of opposed series of fastener elements and a slider operable therealong for interlocking and releasing same, the elements of one series comprising spaced loop members and the elements of the other series comprising elongated flat members, each of which latter has a substantially semi-circular offset portion at the outer edge fitting within a loop member of the other series of elements.
